UNITED STATES PATENT OFFICE

2,279,904

STEREOSCOPE

Donald P. Mossman, Meadville, Pa., assignor to
 Keystone View Company, Meadville Pa., a corporation of Pennsylvania

Application December 21, 1940, Serial No. 371,180

4 Claims. (Cl. 88—29)

This invention relates to optical instruments and has special reference to a stereoscope.

One important object of the invention is to improve the general construction of such stereoscopes.

A second important object of the invention is to provide an improved mounting for a stereoscope.

A third important object of the invention is to provide an improved form of stereoscope adapted for viewing both transparent and opaque stereoscopic pictures and the like.

A fourth important object of the invention is to provide an improved detachable shadow box construction for such a stereoscope.

A fifth important object of the invention is to provide an improved form of stereoscope adapted for use by oculists and optometrists in detection of errors and deficiencies in vision.

With the foregoing and other objects in view, the invention consists in the details of construction, and in the arrangement and combination of parts to be hereinafter more fully set forth and claimed.

In describing the invention in detail, reference will be had to the accompanying drawings forming part of this application, wherein like characters denote corresponding parts in the several views, and in which—

Figure 1 illustrates a side elevation of the complete stereoscope;

Figure 2 illustrates a plan view of the stereoscope with the base omitted, the view being taken from the line 2—2 of Fig. 1;

Figure 3 illustrates a section on the line 3—3 of Fig. 2 with the mount omitted;

Figure 4 illustrates an enlarged section of the joint at the upper part of the mount, the view being a section on the line 4—4 of Fig. 5;

Figure 5 illustrates a fragmentary elevation, partly in section, of the joint shown in Fig. 4;

Figure 6 illustrates a section on the lines 6—6 of Figs. 1 and 9;

Figure 7 illustrates a plan view of the parts shown in Fig. 6;

Figure 8 illustrates a section on the line 8—8 of Fig. 4;

Figure 9 illustrates a side elevation showing the stereoscope removed from the base and used as a hand instrument, both the light box and the shadow box being removed;

Figure 10 illustrates a view somewhat similar to Fig. 9 but with the light box in place;

Figure 11 illustrates a view somewhat similar to Fig. 9 but with the shadow box in place; and

Figure 12 illustrates a detail section to enlarged scale on the line 12—12 of Fig. 1.

In the form of the invention shown in the several views, there is provided a base 10 preferably supported on pads or legs 11. Projecting upward-

ly from this base is a pair of bearing lugs one of which is shown at 12. Through the lugs 12 extends a pivot bolt 13 whereon is mounted the lower end of an arm 14. A stop 15 is provided to limit the swinging movement of this arm in one direction. The stereoscope is provided with a binocular eye-piece 16 in each side of which is a diaphragm 17 on the rear face of which rests a pad or cushion 18 and a stereoscopic lens 19 is held against this pad by a frame 20. A hollow boss or lug 21 extends downwardly from the bottom of the eye-piece 16 at the forward end thereof. A yoke 22 has upwardly extending arms 23 between which the boss 21 fits, the arms being secured to said boss by screws 24. Said yoke also has downwardly extending arms 25 between which is received the upper end of the swinging arm 14. Friction washers or pads 26 are provided between the end of the arm 14 and the arms 25 and a pivot bolt 27 extends through the arms 25, pads 26 and upper end of the arm 14. A stop pin 28 is screwed through one of the arms 25 and has its inner end engaged in an arcuate groove 29 formed in the upper end of the arm 14. This limits rocking movement of the eye-piece 16 on the bolt 27. The boss 21 is provided with a hollow rearward extension 30 and a frame 31 is secured to the under side of the boss and extension by screws 32. The front and rear sides of the frame 31 are channelled as at 33 to receive a slide 34 which has a stop 35 screwed into its under side to limit movement of the slide by engagement with the frame ends. Between the slide 34 and the top of the extension 30 is held a pair of presser plates 36 urged apart by a leaf spring 37 to frictionally resist longitudinal movement of the slide with reference to the eye-piece.

A card and transparency supporting frame 38 has a ground glass plate 39 fitted therein, and extending downwardly from the lower cross bar 40 of this frame is a thumb piece 41. The thumb piece 41 has a forwardly projecting portion 42 spaced below the forward part of the bar 40 so that the rear end of the slide 34 may fit in the space thus provided and be there secured as by screws 43. Projecting forwardly from the lower front face of the frame at each side thereof is a vertically extending T-shaped rib 44 and at the lateral edges of the frame are forwardly extending guard pieces 45, having at their lower ends inturned flanges 46 so that a card C may be positioned in front of the frame as in Fig. 10. The ribs 44 serve to support a transparency C' or the like, as shown in Fig. 9.

A shadow box or hood 47 has its side walls provided with hook-like extensions 48 to hook over the heads of the ribs 44 and thus removably hold the shadow box in front of the frame 38. The top wall of this shadow box is channelled at its rear edge as at 49 to permit insertion of a

transparency or the like when the shadow box is in use.

A lamp housing or box 50 is provided at its sides with ears 51 so that this housing may be detachably secured to the rear face of the frame 39 by screws 52. Slots 53 are provided for ventilation of the box and in one end is fitted a keyed lamp socket 54 having the usual connection cord 55.

The lower end of the arm 14 is provided on each side with friction washers 14a so that, when the screws 13 are tightened, the resistance to rocking motion of the arm 14 will be so regulated that the device may be held in any desired position of adjustment.

In operation, the device may be used either with the base or without the base and held in the hand. It will be seen that the device is easily adjusted to a maximum or minimum elevation, thus affording comfort to the user due to its balance and angularity which enables the user to sit close to the instrument. The construction provides a stable means of support in every position for the upper parts which would otherwise tend to form a top-heavy structure. Further, the method of mounting the binocular provides maximum space for the user's face, since his nose does not engage against a post or the like.

The utility of this device will be seen when it is considered that there are millions of stereographs in the libraries of many individuals who may never be interested in the newer developments; there are also many among this group who are interested in maintaining their present libraries of the standard size stereograph in opaque form and enjoying the modern forms of application, and, of course, there are those who are only interested in the latter. These modern interests have been brought about by the extensive interest that the general public has taken in photography since the advent of the candid camera. To this the successful development of color photography has added a tremendous interest. Thus, it is believed that to develop an instrument that provides for the preservation of a system and the means of practicing another is an invention of the first order and an addition to the art. To be specific about this, the card holder provides for viewing the older and larger size standard stereograph in opaque, a new and more convenient size opaque, stereoscopic format and the added convenience or facility for viewing transparent stereoscopic formats produced in certain popular sizes available. The construction does not necessarily require that the card holder be as large as it is. This is done with a view to forming a background which will prevent the user from seeing beyond that plane most of the time when the holder is extended to within the focal distance of the lens. This is valuable in that, for many people, it prevents the confusion caused by the tendency of the eyes to see beyond the card holder.

As a description of the operation of the device and its several parts has been stated in connection with a description of the parts and their assembly, a résumé of the operation need not, it is thought, be given for an understanding of the invention by those skilled in the art.

I claim:

1. In a stereoscope, focusing means for the eye-piece, a hollow boss extending downwardly from the bottom of said eye-piece and provided with front and rear walls having oppositely disposed passages therein, a spring housing extending rearwardly from the rear wall of said boss and provided with a rear wall having an opening aligned with said passages and with a top wall spaced above said opening, a picture frame carrying sliding bar extending through said opening and passages, and spring friction means disposed in said housing between said top wall and sliding bar.

2. In a stereoscope, focusing means for the eye-piece, a hollow boss extending downwardly from the bottom of said eye-piece and provided with front and rear walls having oppositely disposed passages therein, a spring housing extending rearwardly from the rear wall of said boss and provided with a rear wall having an opening aligned with said passages and with a top wall spaced above said opening, a picture frame carrying sliding bar extending through said opening and passages, spring friction means disposed in said housing between said top wall and sliding bar, spaced bottom wall sections extending rearwardly from the front wall of said boss and forwardly from the rear wall of the housing, and a stop element depending from said sliding bar into the space between said bottom walls.

3. In a stereoscope, picture supporting means including an upright frame including spaced sides having a cross bar extending forwardly from its lower edge, T-shaped picture guides extending upwardly along the front faces of the frame sides whereby to hold a picture against the frame between said guides, and a shadow box having side and top walls, said side walls having their rear edges provided with upper portions adapted to engage the front faces of the frame sides and with lower portions offset forwardly to engage the front faces of the picture guides, said side walls being spaced at such distance as to have their lower portions engage the guides adjacent the outer edges thereof and being provided at the junctions of the upper and lower portions with downwardly opening slots engageable over the tops of said guides.

4. In a stereoscope, picture supporting means including an upright frame including spaced sides having a cross bar extending forwardly from its lower edge, T-shaped picture guides extending upwardly along the front faces of the frame sides whereby to hold a picture against the frame between said guides, and a shadow box having side and top walls, said side walls having their rear edges provided with upper portions adapted to engage the front faces of the frame sides and with lower portions offset forwardly to engage the front faces of the picture guides, said side walls being spaced at such distance as to have their lower portions engage the guides adjacent the outer edges thereof and being provided at the junctions of the upper and lower portions with downwardly opening slots engageable over the top of said guides, said top wall having its rear edge provided with a shallow notch of a width substantially equal to the distance between the stems of the T-shaped guides to permit introduction and removal of pictures.

DONALD P. MOSSMAN.
